United States Patent Office

Des. 186,833
Patented Dec. 8, 1959

186,833

DISPLAY RACK FOR MILLINERY OR THE LIKE

Joseph Nadel, New Milford, N.J.

Application January 23, 1959, Serial No. 54,283

Term of patent 14 years

(Cl. D80—10)

Fig. 1 is a perspective view of a display rack for millinery or the like embodying my new design;

Fig. 2 is a right side elevational view thereof; and
Fig. 3 is a top plan view thereof.

I claim:

The ornamental design for a display rack for millinery or the like, as shown.
